Primary Examiner — Jeffrey D Asch(74) *Attorney, Agent, or Firm* — Banner & Witcoff, Ltd.**CLAIM**

The ornamental design for a handset, as shown and described.

DESCRIPTIONFIG. 1 is a perspective view of a handset showing our new design;
FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken-line showing of the environmental structure of the handset, as well as the unshaded regions therein, are for illustrative purposes only and form no part of the claimed design.
